UNITED STATES PATENT OFFICE.

WALTER F. KASPER, OF FAIRMONT, MINNESOTA, ASSIGNOR TO FAIRMONT GAS ENGINE & RAILWAY MOTOR CAR CO., OF FAIRMONT, MINNESOTA, A CORPORATION.

CUTTER-BAR CONTROL FOR WEED-MOWERS.

1,328,836.

Specification of Letters Patent. Patented Jan. 27, 1920.

Application filed August 18, 1916. Serial No. 115,699.

To all whom it may concern:

Be it known that I, WALTER F. KASPER, a citizen of the United States, resident of Fairmont, county of Martin, State of Minnesota, have invented certain new and useful Improvements in Cutter-Bar Controls for Weed-Mowers, of which the following is a specification.

My invention relates to machines used for 10 mowing grass and weeds on each side of a railroad track and the object of the invention is to simplify and improve the system of control mechanism of the cutter bars to the end that less labor will be involved and 15 the operators of the car will have quicker control of the cutting mechanism.

Other objects of the invention will appear from the following detailed description.

The invention consists generally in various 20 constructions and combinations, all as hereinafter described and particularly pointed out in the claims.

In the accompanying drawings forming part of this specification,

25 Fig. 1 is a plan view of a small flat-car of the general type used by railroad section men, with my improved weed mowing mechanism and lever control mounted thereon,

30 Fig. 2 is a side view, partially in section, of the same,

Fig. 3 is an end view, also partially in section, showing a cutter bar lowered to a horizontal position,

35 Fig. 4 is a similar view, showing the mowing mechanism on one side of the car lowered to substantially its working level,

40 Fig. 5 is a similar view, illustrating the mowing mechanism raised to an inoperative position for movement to another point on the railroad.

In the drawing, 2 represents a flat-car of the type usually used on railroad sections, having an axle 3 and carrying wheels 4 to 45 roll upon the track 5. 6 is a shaft mounted in the frame of the car and having a clutch 7 and variable speed drive belts 8 and 9 connecting the shaft with the axle 3. By shifting this clutch the axle may be driven at different speeds, as desired. For instance, there may be one working speed and another when the cutter-bars are raised for moving the car from place to place on the line. This shaft 6 is geared at 10 to a counter shaft 11 50 which has a driving belt connection 12 with

the source of motive power, such as a gas engine 13' mounted on the platform of the car. A clutch 7a is also provided on the shaft 6 and by means of these two clutches the operators of the car can control the movement of the cutter bars and at any time can disconnect these clutches and drive the car through the high speed belt 9 when it is desired to move it rapidly from one point to another on the section or division of the road.

The mowing apparatus proper, which I mount on each side of the car and connect with the shaft 6, I will now describe in detail, and as the mechanism on one side corresponds to that on the other I will use the same reference numerals on both sides with the addition of the exponent "a" on one side to indicate the different parts.

13 is a bevel gear, mounted to be driven 75 through the clutch 7a and meshing with a pinion 14 on a stub shaft 15 which is journaled in a bracket 16 and carries a crank disk 16'. A bracket 17 is secured to the frame of the car and a shaft 18 is journaled 80 therein, concentric with the shaft of the crank disk 16' and a bar 19 is mounted on this shaft and projects outwardly therefrom and is pivotally connected at 20 to a shoe 21. A pitman 22 is pivoted at one end on the crank 85 disk 16' and at its other end is pivotally connected to a cutter bar 23 that is mounted to slide in the shoe 21 and the usual guide bar 24. A brace 25 is mounted at one end on the bar 19 and at its other end is pivotally 90 connected with a bracket 26 on the frame of the car, the pivot of this brace on the bracket being concentric with the axes of the shafts 15 and 18 to permit freedom of vertical movement of the cutter bar, as will 95 hereinafter appear.

An arm 27 is secured to the shoe 21 and projects upwardly therefrom and a similar arm 28 is loosely mounted at one end on the shaft 18 and is free to rock thereon and 100 has a flexible connection 29 with the upper end of the arm 27 for simultaneous movement. The arms 27 and 28 project in substantially the same vertical plane, and while not exactly parallel with one another, have 105 substantially a parallel link motion to the extent that movement of one arm imparts a corresponding travel to the other arm. A chain 30 extends from the upper end of the arm 28 around a sheave 31 mounted in a 110

block 32 that is pivoted at 33 on the sill of the car and the other end of the chain 30 is connected to a lever 34 movable over a quadrant 35 and positioned to swing in a vertical plane lengthwise of the car and the track, so that the operator, standing on the car platform, can move the lever forward or backward and face the work and the direction the car is moving while operating the lever. This lever is provided with the usual locking latch 36 by means of which the operator can hold the lever in any desired position on the quadrant. A tension spring 37 connects the arm 27 with the frame of the car and yieldingly resists the downward pull of the shoe and guide bar 24 and cutter bar. The frame 37' is mounted on the car to extend transversely thereof and is secured to the platform.

Upon the bar 19 I provide a clamp 38 having a flexible connection 39 passing over a sheave 40 mounted on the frame 37' to a second sheave 41 and from thence to an operating lever 34^a corresponding to the one described and operating in the same manner and in a parallel vertical plane for the purpose of lifting the bar 19 from the horizontal position shown in Fig. 3 to the raised position illustrated in Fig. 5, said bar swinging on the shaft 18 as an axis during this movement. The levers 34 and 34^a are spaced apart a sufficient distance to allow the workman to stand in the rear of them and operate one lever with one hand and the other lever with the other hand, and as both levers move in the same direction, it is evident that a workman will have easy and quick control of the cutter bars and their supports, and as the workman will be facing the track over which the car is moving, he can easily watch for any obstruction and raise the cutter bars immediately whenever occasion requires, the tension of the spring 37 assisting the operator in the initial upward movement of the sickle bar.

A second clamp 42 is mounted on the bar 19 and has a flexible connection 43 passing over a sheave 44 and attached at 45 to said sheave. This sheave 44 is also mounted in the frame 37' and has a cam 46 on its outer face and a flexible connection 47 is attached at one end to said cam and passes under a sheave 48 and is connected to a tension spring 49 which is arranged transversely of the car and is secured to the frame on the opposite side thereof. This connection and the cam 46 are for the purpose of equalizing the tension on the spring 49 for, as the cutter bar is lowered, and the spring is extended, its leverage on the sheave with which it is connected will gradually decrease as indicated, in Fig. 3, the cam being so made that the decrease in leverage of the spring thereon will be proportionate to the extension of the spring. The result is that the pull of the

spring to raise the bar 19 will be substantially uniform during the vertical movement of the bar, the cam decreasing the leverage of the spring on the sheave in proportion to the separation of the spring coils. When the cutter bar is raised to the position shown in Fig. 5 a rod 50 is thrust through a hole in the bar and secured by suitable means, such as nuts 51, and the mowing apparatus will be securely held in its raised, inoperative position and the car may then be moved to some other point on the section or division of the line.

With this apparatus the men on the car have perfect control of the mowing mechanism and as they stand facing the front of the car or the direction of travel, they will have perfect view of the cutter bars and the road ahead. The manner of mounting the bars on the frame of the car provides for considerable angular movement of both the cutter bar guide and the supporting bar, making it possible to raise them sufficiently to clear cattle guards or other obstructions without the necessity of stopping the forward motion of the machine. The manner of mounting the bars and the balancing springs connected therewith insures ease of operation, and the arrangement of the operating levers provides plenty of room for the workmen and a clear vision ahead of the car.

I claim as my invention:

1. The combination, with a railroad car platform, of a frame mounted transversely thereof and extending from side to side of said platform, bars pivoted at their inner ends on said platform and mounted for vertical oscillation, guide bars pivoted on the outer ends of said first named bars, cutter bars mounted in said guide bars and a suitable operating mechanism therefor, sheaves mounted on said transverse frame at intervals across said platform, flexible means having running connections with said sheaves and with said pivoted bars and said guide bars respectively, and levers mounted in pairs upon opposite sides of the middle portion of said platform and connected respectively to said flexible means, said levers of a pair being spaced a suitable distance apart for an operator to stand between them and movable forward and backward in the direction of travel of said car, whereby a workman can manipulate a lever with each hand and face the work ahead of the car, springs connected with said platform bars for normally resisting downward movement thereof, and means for equalizing the tension on said springs as said bars are lowered.

2. The combination, with a car, of a bar pivoted thereon, a cutter bar guide and shoe pivoted on said bar, levers mounted on said car and having flexible connections with said bar and shoe for tilting them, a sheave

mounted on said car and provided with a cam surface, flexible means connecting said bar with said sheave, a spring normally tending to resist the downward pull of said flexible means, and a connection between 5 said cam surface and said spring, the leverage of said cam increasing proportionately to the extension of said spring.

3. The combination, with a railroad car, 10 of a bar pivotally supported in the frame of said car at one side thereof and projecting outwardly therefrom, a shoe pivotally supported on the outer end of said bar, a cutter guide bar carried by said shoe, an 15 arm rigidly mounted on said shoe and projecting upwardly therefrom, means normally resisting downward movement of said pivoted bar and said cutter bar, a driving mechanism for said cutter bar, flexible 20 means connected with said pivoted bar and having a running connection with said car, a spring connected with said flexible means, means for equalizing the tension on said 25 spring as said bar is lowered, a pivoted bar having a flexible connection with said ratchet bar and operating levers mounted on the car and having flexible connections with said pivoted bar and with said pivoted arm, said operating levers being mounted 30 for forward and backward movement on the car to allow a workman to face the work while the car is in motion.

4. The combination, with a railroad car, 35 of a bar pivotally supported on the frame of said car at one side thereof and projecting outwardly therefrom, a shoe pivotally supported on the outer end of said bar, a

cutter guide bar carried by said shoe, an arm rigidly mounted on said shoe and projecting upwardly therefrom, a helical spring 40 connecting said arm with said car and normally resisting downward movement of said pivoted bar and said cutter bar, a driving mechanism for said cutter bar, a sheave mounted on said car, flexible means connected 45 to said pivoted bar and passing over said sheave, a spring connected to said flexible means, a cam device in connection with said sheave for equalizing the tension on said spring as said bar is lowered, an upright 50 pivoted bar near said car and having a flexible connection with said ratchet bar, and operating levers mounted on said car and having flexible connections with said pivoted bar and with said pivoted arm, said 55 operating levers being mounted for forward and backward movement on the car to allow a workman to face the work while the car is in motion.

5. The combination, with a car, of a bar 60 pivoted thereon, a cutter bar guide, a shoe pivoted on said bar, levers mounted on said car and having flexible connections with said bar and shoe for tilting them, a spring 65 connected with said bar for normally resisting downward movement thereof, and means for equalizing the tension of said spring as said bar is lowered.

In witness whereof I have hereunto set my hand this 25th day of July, 1916.

WALTER F. KASPER.
